DENTAL TOOL

Alexander S. Gross, Chicago, Ill.

Application August 20, 1930, Serial No. 476,490
Renewed September 11, 1933

2 Claims. (Cl. 32—10)

My invention relates to dental grinding tools, and more particularly to an attachment for dental grinding tools which is so arranged as to maintain a flow of water against the periphery of the stone to cool the same.

It is well known that the heat produced by the grinding operation of a dental grinding tool is painful and at times unbearable to the patient. If the heat could be eliminated, the hypo-sensitivity of the nerve resulting from the heat and causing the pain could also be eliminated.

I have found that by a proper construction of parts it is possible to maintain a flow of water upon the stone during the grinding operation, although the grinding tool itself may be small and the use of the tool in the mouth allows for very little space for an attachment of this kind.

In order to apprise those skilled in the art how to construct and practise my invention, I shall now describe a preferred embodiment thereof.

In the drawing:

Figure 1 is a perspective view of a dental grinding tool embodying my invention;

Fig. 2 is a vertical sectional view of the same; and

Fig. 3 is an end view showing the manner in which the guard surrounds the grinding stone and supports the jet in order to direct the water against the stone.

By referring to the drawing, it will be noted that I have shown in Fig. 1 a standard form of grinding tool comprising a handle portion 1, a grinding stone 2 carried by a shank 3, which shank is locked to the handle portion 1 by the usual chuck 4, there being a flexible driving connection 5 at the far end of the handle.

My invention comprises specifically the provision of a bracket or other supporting structure, which, as shown in the drawing, comprises a sleeve 6 fitting upon a part of the handle portion, the sleeve having a slot 7 therein into which fits a pin 8 projecting from the handle portion so as to prevent relative rotation of the sleeve. The water supply is provided by a jet 10 suitably supported above handle portion 1 by upstanding brackets 11 and 12. Bracket 11 extends forwardly and upwardly from the forward end of sleeve 6. A suitable guard, preferably semi-circular in shape, is carried by bracket 11 in a position about the upper part of the periphery of stone 2 to prevent injury to the cheek or roof of the mouth in the event stone 2 should slip during the grinding operation. At the same time, guard 14 provides a suitable support for the forward end of jet 10. Jet 10 may be tapered forwardly and

bent downwardly, the end of the bent portion being threaded to receive a locking nut 15. This threaded end passes through the upper part of guard 14 so that locking nut 15 may be threaded upon the end of the jet to hold the same suitably secured to guard 14.

Bracket 12 may extend upwardly in any suitable manner from sleeve 6 so as to carry the rear end of jet 10. I preferably provide an opening 16 in bracket 12, which receives the enlarged portion 17 of the rear end of jet 10 by a tight sliding fit. Jet 10 may be connected to the source of water supply by any suitable connection, such as by a flexible tubing 18.

The construction of the dental grinding tool shown herein is well known to those skilled in the art. Shank 3 of grinding stone 2 extends rearwardly into the handle portion, as shown by dotted line in Fig. 2. The head member 19 is carried upon shank 3 to fit against shoulder 20 of casing 21. Chuck 4, when operated, locks grinding stone 2 in position by suitably gripping its shank 3, as is well known; consequently, sleeve 6 cannot accidentally slip from handle portion 1. Sleeve 2 is adapted to slide into position on casing 21 of handle portion 1 so that the forward edge thereof, designated by 22 in Fig. 2 will lie against the rear face of head 19 on shank 3. This arrangement provides a positive lock for sleeve 6 and also prevents it from being accidentally released while upon handle 1.

It will be observed that the tool shown herein affords a very simple means of furnishing a constant supply of water to the periphery of the stone so as to eliminate heat produced during the grinding operation upon the tooth. The parts are few and small and very compactly arranged. They do not interfere with the use of the grinding tool, but, on the contrary, provide a guard about the grinding stone which prevents accidental injury to the patient in the event the stone slips.

Various modifications of the detail and arrangement may be made without departing from the spirit and scope of the invention.

I claim:

1. A sleeve for insertion upon a handle of a dental grinding tool, comprising a relatively straight tubular portion and a relatively tapered tubular portion, the smaller end of said tubular portion engaging a shoulder on said tool to prevent longitudinal displacement of said sleeve in one direction, the said straight tubular portion having a slot receiving a stud on said handle to prevent rotational movement and longitudinal

displacement in the other direction, a bracket extending forwardly and upwardly from the smaller end of said tapered tubular portion, a guard carried by said bracket and spaced from 5 said tool, a water jet supported at its outlet by said guard to allow water to drop upon said tool, and an upwardly extending second bracket on said sleeve to support the other end of said jet.

2. A sleeve for insertion upon a handle of a 10 dental grinding tool, a portion of said sleeve at one end engaging a shoulder on said tool to prevent longitudinal displacement of said sleeve in one direction, the other end of said sleeve having

a slot receiving a stud on said handle to prevent rotational movement and longitudinal displacement in the other direction, a bracket extending forwardly and upwardly from said sleeve substantially at said shoulder engaging portion, a 80 guard carried by said bracket and spaced from said tool, a water jet supported at its outlet by said guard to allow water to drop upon said tool, and supporting means on said sleeve spaced from said bracket for supporting the other end of 85 said water jet.
